PORTRABLE CARPET SAMPLE HOOK

Raymond R. Byrnes, 141 S. Dillon St.,
Los Angeles, Calif. 90057

Filed Jan. 15, 1968, Ser. No. 10,156

Term of patent 14 years

Int. Cl. D8—02

U.S. Cl. D54—13

I claim:

The ornamental design for a portable carpet sample hook, as shown and described.
